UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAFT-GEAR.

1,066,530.

Specification of Letters Patent.

Patented July 8, 1913.

Application filed August 10, 1910. Serial No. 576,576.

To all whom it may concern:

Be it known that I, JOHN M. ROHLFING, residing at St. Louis, Missouri, and being a citizen of the United States, have invented certain new and useful Improvements in Draft-Gear, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a longitudinal view taken on line 1—1 of Fig. 2. Fig. 2 is a view taken approximately on line 2—2 of Fig. 1. Fig. 3 is a transverse sectional view, taken on line 3—4, Fig. 1. Fig. 4 is a similar section on line 4—4, Fig. 1. Fig. 5 is a diagrammatical view, showing operative position of parts.

This invention relates to new and useful improvements in draft-rigging of the friction type, wherein draft sills are utilized as carrying members and the friction elements are supported between the draft sills in such relation that minimum strain is applied to the draft sill in the operation of the device.

Referring to the parts A A' are the draft sills which may be of any convenient form but preferably of rolled channel shape.

B is the drawbar. C the spring or nested springs, as may be desired.

D is the yoke or strap inclosing the operative parts.

E E are the draft lugs on the draft sills.

The yoke D is of a general U-shape horizontally disposed, and fitted between the open end of which is the inner end of a draw-bar B. Fitting between the sides of the yoke and of a depth substantially equal to the depth of the same and suitably fastened thereto is a housing, shown in Fig. 1 to be a hollow casting, the front end of which abuts the inner end of the draw-bar B, and is formed into a front pocket F having laterally disposed openings, each opening facing the adjacent sill A and forming a housing for the inner ends of the front links 2, hereinafter described. Similarly

the rear end of the housing fits between the

sides and contacts with the crotch of the yoke and is formed similar to the front pocket F to constitute a rear pocket F' for the rear links 2. Intermediate the pockets F, F' is the spring C which abuts at each end against one of the longitudinally movable transversely extending friction blocks or followers b b' which in operation contact with the transversely moving friction wedge members a a a' a' as hereinafter described.

Extending longitudinally and filling the gap between the follower stops E E at each side of the device are socket plates or castings 1, connected at each end by means of links 2 with the front and rear pockets F F', pins 3 being provided for that purpose. Each of the socket plate members 1 is provided with suitable sockets opening inwardly in which sockets are received the enlarged or relatively angular outer ends 75 of the wedges a a' which wedges extend inwardly as is best shown in Fig. 2 toward the longitudinal axis of the device there being a gap or space 4 between the inner ends of the said wedges a a' into which projects 80 the widest portion of the intermediate friction blocks or followers b b' against which in turn bears the spring C above referred to, the said plates serving as wedge guides and retaining means permitting longitudinal movement—and causing transverse movement—of said wedges in operation whereby, with the yoke, the operative parts are supported in co-operative relation. The members 1 are provided with enlargements 90 5 at each end in which are seated the pins 3 of the links 2 and between the enlargements 5 said members 1 are provided with top and bottom flanges 6—7 and intermediate stiffening ribs 8 which extend longitudinally of 95 the device, each casting or guide plate 1 being free to move transversely or inwardly from the draft sills A when impelled by the links 2 during buffing or pulling, and the flanges 6—7 are widened inwardly, as 100 shown by the dotted lines 8 in Fig. 2 to provide the seats necessary for the angular heads of the friction members a a'.

The followers or friction members b b' are provided with embossments 9 which serve as seats for the springs C above referred to while the opposite faces of the said blocks b b' are relatively frusto-pyramidal so as to provide on the outer sides thereof wide plane bearing surfaces for the blocks 110

a a' with inclined plane surfaces directed inwardly against which the inclined or wedge shaped ends of the friction wedges *a a'* are driven in the operation of the device.

- 5 In operation, the action is as follows:— In buffing the drawbar B is driven inwardly as indicated by the arrow in Fig. 2 thereby impinging the front pocket F and carrying the yoke D together with its attached pocket 10 F rearwardly, at which time the angular positions of the links 2 will be changed, thereby drawing inwardly the plates 1 and crowding the friction members *a a'* inwardly to the extent of the inward movement of the 15 side members 1 at which time friction will be developed between the forward faces of the wedges *a* and the inner face of the pocket F—also between the rearward faces of the members *a* and the forward face of the friction block *b*. Likewise there will be some longitudinal travel of the wedges *a* as indicated in the diagrammatical view Fig. 5. At the opposite, or rear, end of the device, friction will be developed between the 25 wedges *a'* and the block *b'*, also between the rear faces of the castings or socket plates 1 and the draft lugs E. As the drawbar continues to move inwardly, the friction is increased, owing to the compression of the 30 spring C but the gap 4 being limited and the inward travel of the socket plates 1 likewise being limited, it is evident that before excessive compression of the springs can take place, the members will come to a stop 35 thus avoiding such excessive compression of the spring as will cause it to set. In pulling, the condition is reversed and the rear pocket will impinge against the wedges *a'* which will contact with the block *b'*, combining 40 the spring C and forcing the block *b* into contact with the wedges *a*, thereby moving the wedges longitudinally but pulling inwardly the guide or socket plates 1 and forcing said wedges to travel transversely of the device.

Extending transversely above the operative members of the draft gear are channels 10 which are connected by means of their upturned web portions 11 and rivets 50 12 with the draft sills A as is best shown in Figs. 1—3—4, the channels serving to tie the draft sills together.

What I claim is:—

1. In a draft gear, the combination comprising transversely movable socket plates, an intermediate spring, transversely extending friction blocks forming followers for said spring, and transversely movable friction wedges disposed between said blocks 60 and plates.

2. In a draft gear, the combination comprising transversely movable socket plates, an intermediate spring, transversely extending friction blocks forming followers

for said spring, and pairs of transversely movable friction wedges co-acting with said plates and actuated by said friction blocks to restore the plates to their normal position.

3. In a draft gear, the combination comprising transversely movable socket plates, an intermediate spring, transversely extending friction blocks disposed at opposite ends of said spring, pairs of transversely movable friction members engaging said plates, said blocks and members having co-acting beveled faces for causing transverse movement of said plates.

4. In a draft gear, the combination comprising transversely movable socket plates, an intermediate spring, transversely extending friction blocks forming followers for said spring, friction wedges controlling said plates longitudinally and transversely movable by the action of said blocks when moved by said spring and means connecting said plates.

5. In a draft gear, the combination comprising transversely movable socket plates, an intermediate spring, transversely extending friction blocks controlled by said spring, longitudinally movable friction wedges controlled by said blocks and spring for causing transverse movement of said plates and wedges.

6. In a draft gear, the combination comprising transversely movable socket members, longitudinally movable transverse friction blocks, transversely movable friction wedges constituting an engagement between said blocks and members and means for connecting said socket members.

7. In a draft gear, the combination comprising transversely movable socket members, longitudinally movable transverse friction blocks, transversely movable friction 105 wedges engaging said members, said blocks and wedges having co-acting means for transferring the longitudinal movement of the blocks into transverse movement of the wedges when the wedges and blocks are returning to their normal position, and means for moving said wedges and blocks longitudinally.

8. In a draft gear, the combination comprising transversely movable socket members, longitudinally movable transverse friction blocks, transversely movable friction wedges disposed between said members and one end of said blocks and engaging said members, said wedges and blocks having co-acting beveled faces, and means for causing longitudinal movement of said wedges and blocks and, through said beveled faces, causing transverse movement of said socket members.

9. In a draft gear, the combination with a single spring, of friction blocks and wedges forming friction producing elements

controlled by said spring, and transversely movable spaced apart socket plates extending longitudinally on opposite sides of said elements and engaged by said wedges and held from longitudinal movement between spaced draft lugs.

10. In a friction draft gear, the combination of movable friction producing elements, transversely movable guides in contact with 10 and adapted to actuate some of said elements, a coupler, and a continuous connection between said coupler and guide for moving said guides transversely.

11. In a draft gear, longitudinally disposed and relatively fixed wedge guides, wedges, an intermediate spring, friction blocks between said guides and between said spring and the wedges, in combination with means for causing transverse travel of said 15 guides.

12. In a draft gear, transversely movable, longitudinally extending wedge guide and supporting means, transversely movable wedges disposed between said means adjacent opposite ends thereof and interposed coöperating friction producing elements in engagement with and actuating said wedges on the release movement of the elements to their normal position.

13. In a draft gear, transversely spaced and longitudinally fixed combined guides and wedge socket members, in combination with means for moving said members transversely, and coöperating friction producing 35 elements interposed between said members adapted to oppose the transverse movement of said members.

14. In a draft gear, the combination comprising transversely movable socket plates, 40 a spring disposed between said plates, a transversely extending friction block engaging one end of said spring, and a transversely movable friction wedge disposed between said block and one of said plates.

15. In a draft gear, the combination of spaced apart sills, a pair of spaced socket plates disposed between said sills and movable transversely thereof, a yoke disposed between said plates and link connections between each of said plates and said yoke, and

friction elements disposed between each of said plates and said yoke.

16. In a draft gear, the combination of transversely movable socket plates, a yoke disposed between said plates, link connections between each of said plates and yoke, and resiliently controlled means disposed between said plates opposing inward movement of the same.

17. In a draft gear, the combination of 60 transversely movable socket plates, a yoke disposed between said plates, a connection between each of said plates and yoke whereby a longitudinal movement of said yoke will move said plates transversely, friction 65 elements disposed between and engaging said plates, and means acting on said elements tending to move the same against the plates.

18. In a draft gear, draft sills having 70 longitudinally spaced apart draft lugs fixed thereto, a pair of transversely movable plates, each plate fitting between the lugs on one of the sills, a longitudinally movable member disposed between said plates, a connection between each of said plates and said member adapted to draw said plates toward said member when the latter is moved in either direction from its normal position, and friction producing means disposed between said plates and in engagement therewith adapted to oppose the movement of said member.

19. In a draft gear, a pair of longitudinally disposed and relatively fixed plates, a 85 longitudinally movable member disposed between and adapted to limit the inward movement of said plates, a connection between each of said plates and said member adapted to draw said plates toward said member when the latter is actuated, and means cushioning the movement of said plates toward said member.

In witness whereof I have hereunto set my hand in the presence of two witnesses.

JOHN M. ROHLFING.
